UNITED STATES PATENT OFFICE.

JNO. S. GISBORNE, OF BIRKENHEAD, AND WILLIAM SIMPSON, OF LIVERPOOL, ENGLAND.

IMPROVEMENT IN RENDERING COMPASSES INSENSIBLE TO LOCAL ATTRACTION.

Specification forming part of Letters Patent No. 41,839, dated March 8, 1864.

To all whom it may concern:

Be it known that we, JOHN SACHEVERELL GISBORNE, of Birkenhead, in the county of Chester, telegraphic engineer, and WILLIAM SIMPSON, of Liverpool, in the county of Lancaster, gentleman, both in that part of the United Kingdom of Great Britain and Ireland called England, have invented a new and useful Improvement in Means for Rendering Ships' and other Compasses Inensible to Local Attraction; and we do hereby declare that the following is a full and exact description of the construction and operation thereof, reference being had to the accompanying sheet of drawings, making a part of this specification, and to the letters of reference thereon—that is to say:

Our invention consists of the use or employment of electricity to render insensible to local attraction or to overcome or countercheck the local influences which have so often and so seriously affected the magnetic needles or their equivalents in mariners' compasses; and although our said invention is more particularly serviceable in compasses to be used on board ship, it is not exclusively so applicable, as it may advantageously form part of or be used in connection with compasses to be elsewhere employed.

The best mode or arrangement with which we are acquainted for carrying our said invention of "the use or employment of electricity" for the purpose above named into effect consists in passing a current of electricity from an ordinary battery through a coil of insulated copper wire wound around a hollow conical or semi-spheroidal compass - box, or wound around a hollow conical or semi-spheroidal shaped dish encircling the compass-box. In either of these arrangements the magnetic or compass needle rests on a center point in the usual way at a short distance below a horizontal line drawn across the termination of the said coil and below the mouth or termination of the conical or semi-spheroidal shaped box or dish, the leading features of construction of the compasses at present in use being retained.

To enable others to manufacture and bring compasses constructed according to our invention into practical use, we will now describe more particularly the arrangements

hereinbefore mentioned, and in doing so reference will be made to the illustrative sheet of drawings herewith, in which—

Figure 1 is a perspective view, Fig. 2 a side elevation with part of the binnacle-frame removed, Fig. 3 a vertical section, and Fig. 4 a bird's-eye view with the cover removed, all of a binnacle and compass for use at sea, and with a conical-shaped compass-box. Fig. 5 is a side elevation with part of the binnacle-frame removed, Fig. 6 is a vertical section, and Fig. 7 is a bird's-eye view with the cover removed, all of a binnacle and compass for use at sea, the ordinary compass-box being encircled by and attached to a semi-spheroidal shaped dish, which latter supports the pin on which the needle and card are balanced.

In Figs. 1, 2, 3, and 4 the same letters of reference denote the same parts. *a* represents the binnacle; *b*, the compass-bow; *c*, the steel pin for carrying the needle *d* and card *e*; *f*, the compass-box, made of sheet-copper or other material into the conical shape shown, and supported on gimbals *g*, as in ordinary compasses. On the outer surface of the said conical compass-box *f* there are fastened by soldering or otherwise a number of projecting pins or pieces, *h*, which keep the insulating-wires *i* in their places around the said compass box or cone *f*. The insulated wires *i* are here shown to be two in number; but one only or any larger number may be employed. At *j* they are connected, after sufficient slack has been left for free movement of the compass, to and communicate with the battery *k*, (shown as of the ordinary "sulphate" description,) although any other kind of battery or means of maintaining a continuous current of electricity would answer the same purpose; *l*, the glass cover. *m* shows a protecting cover or hood, of gutta-percha or other material, preferably impervious to moisture.

In Figs. 5, 6, and 7 like letters of reference denote the same parts. *a'* represents the binnacle; *b'*, the compass-bow; *c'*, the needle-carrier; *d'*, the needle; *e'*, the card; *f'*, the compass-box, such as is at present in use, and to which is here shown attached the semi-spheroidal shaped dish or vessel *g'*, that both of them may be carried on or by the gimbals *h'*; *i'*, the glass cover; *j'*, the projecting pins; *k'*, the insulated circuit wire or wires or communi-

cator or communicators of the electricity generated in the battery l' , and connected by the screws m' ; n' , the gutta-percha or other protecting-hood.

To arrange or set either of the apparatus above described for use, it is only necessary to connect the wires to the battery, when, if the insulation is good, a continuous current of electricity passes from one pole of the battery to the other through the coil, and in so doing the effect is to counteract practically all local attraction of the magnetic needle in ships' and other compasses.

Having now described the nature of our said invention and the best construction or arrangement of parts with which we are acquainted for carrying the same into effect, we would have it understood that we do not confine ourselves to the use or employment of the apparatus herein described, nor to the use or employment of any particular kind of apparatus; but

What we claim as our invention, and what we have protected by British Letters Patent of date the 14th February, 1863, No. 401, is—

By means of electricity, however obtained, rendering compasses, or the magnetic needles in compasses for ships and other purposes, insensible to local attraction, convenient practical constructions and arrangements being illustrated on the accompanying sheet of drawings, and herein delineated.

Signed and sealed by the said JOHN SACHEVERELL GISBORNE and WILLIAM SIMPSON, at Liverpool, aforesaid, this 31st day of March, 1863.

JOHN SACHEVERELL GISBORNE. [L. S.]
WILLIAM SIMPSON. [L. S.]

Before us—

JOHN THOMSON KING,
Patent Agent, 4 Clayton Square, Liverpool.
JOHN DAVIES,
Clerk to the said John Thomson King.
